Fig. 4.

Fig. 1.

FIG. 1 is a side elevational view, in reduced scale, of an underfloor wiring duct unit showing our new design, portions of the duct unit being broken away for convenience in illustration;

FIG. 2 is a fragmental perspective view of the underfloor wiring duct unit of FIG. 1, showing an access opening of the duct;

FIG. 3 is a fragmental side elevational view of the duct unit showing the access opening of FIG. 2;

FIG. 4 is a fragmental top plan view of the duct unit showing the access opening of FIG. 2; and

FIG. 5 is an enlarged sectional view taken along the line 5—5 of FIG. 1.

The dominant features of our design are the contours of the duct portions which define the access openings therein as shown more particularly in FIGS. 2, 3, 4, and 5.

We claim:

The ornamental design for an underfloor wiring duct unit, as shown and described.
